APPARATUS FOR DISTILLING MATERIALS.

Application filed January 20, 1921. Serial No. 438,617.

The invention relates to an apparatus for the treatment of materials containing a volatile content, such as coals, oils, mixtures of coal and oil, ores, etc.

5 The invention more particularly consists in improved apparatus for subjecting finely comminuted carbonaceous material to a relatively low heat treatment to obtain a maximum yield of oils from the carbonaceous 10 material with a minimum yield of fixed gases, and to recover the residue in its finely divided state in a carbonized form.

15 My improved apparatus is particularly adapted for use in carrying out a process for the treatment of comminuted carbonaceous materials, such as coals, in which it is a salient feature not only to increase the total 20 yield of oil products, but to obtain a different product in that the oils yielded carry a substantially greater percentage of low boiling point oils than would otherwise be produced by present day processes where larger size materials and higher temperatures are employed. These improved results are obtained by treating the coal or like material 25 having a hydrocarbon content while in an exceedingly fine state of division, in keeping the material in motion and under agitation while undergoing a heat treatment, and in 30 employing temperatures just sufficient to volatilize the oils at their respective boiling points from coal particles which are so fine in size as to require only the minimum of heat penetration, thereby avoiding the excessive 35 temperatures which are necessary when heating coarse material, and which excessive temperatures causes two general changes in the oil vapors, one being changing vapors into fixed gases, and the other converting 40 part of the low boiling point oil vapors into higher boiling point vapors.

The apparatus preferably consists of a plurality of alternate stationary and rotary heated hearths, over the surfaces of which, 45 the material progressively advances. The stationary hearths are provided with rabbles which serve to advance and assist to heat the material during its passage over the surfaces of the movable hearths, and the movable hearths are likewise provided with rabbles which serve to advance and assist to heat the material during its passage over 50 the stationary hearths. Coal and all other

materials, when treated in coarse sizes, say approximately $\frac{1}{4}$ ", require relatively low 55 temperatures to treat the exterior surfaces but require relatively high temperatures to cause heat penetration of the coarse particles to treat their interiors; therefore, owing to these necessary abnormally high temperatures, while volatile products come off as the particles attain the low temperature, they are then changed in character by the higher temperature, the high temperature necessary for penetrating the coarse particles 60 having a further detrimental effect, that of causing the particles undergoing treatment to fuse and agglomerate, which can be avoided by carrying out such treatment in the present apparatus. 65

To avoid these changes of the oil vapors I reduce the coal or other material to the economic limit of fineness so that in effect the particles are practically all surface and no interior, thereby enabling the application 75 of the minimum temperature to cause the vaporizations and consequently avoiding conversion of vapors to fixed gases and light boiling point oils to higher boiling point oils, and also preventing the fusion or agglomeration of the carbonized particles. 80

The material, when introduced to the retort, travels successively and alternately over the upper surfaces of the moving and stationary hearths and is subjected, throughout its travel, to heat transmitted from the interiors of both moving and stationary hearths, which interiors are heated by hot gases travelling therethrough. With this construction, the top and bottom surfaces of 90 each hearth and also the rabbles constitute actual heating surfaces. When great heat economy is desired and when vapors produced at different temperatures are to be collected separately, the material being treated 95 is caused to run counter-current to the direction of flow of the heating gases, so that the volatiles distilled at progressively increasing temperatures are removed in the order produced, and in separate classes corresponding to said progressive temperatures. As the material, in its progress along the path of travel, reaches a zone of temperature as hot as the boiling point of each class of oil in turn, such oils are successively 100 volatilized and then separately taken off, 105

those of the lowest boiling point first, and as the material reaches the hotter zones, those of higher boiling points and so on, the last to be volatilized and taken off being of course those of highest boiling point at the hottest heat zone in the path of travel.

The present invention thus enables materials, such as coals, oils, shales, oil sands, or mixtures of oil and coal to be continuously treated to yield their volatile constituents at a minimum temperature and to enable the vapors which pass from the material at various temperatures to be separately collected. As an example of the operation of the apparatus in carrying out the process above mentioned, if finely comminuted coal is being treated, the same passes through the retort in a direction opposite to the path of incoming gases and is maintained in a state of motion and agitation during its heat treatment, so that when this material is subjected to a temperature of approximately 350° C., the volatiles will be quickly vaporized, while the residue will not agglomerate, but is collected in the form of carbonized particles in substantially the same state of sub-division as the green fuel introduced to the retort, but of course freed of all of its volatiles or such portions as may be desired. The volatiles thus recovered are in the form of valuable oils, with a minimum of fixed gases. The oils of low boiling points thus produced are exceedingly valuable, whereas if the material were subjected to a high temperature, these low boiling point oils would be converted into fixed gases and other less desirable coal products.

While I have described an apparatus as particularly applicable to the treatment of pulverized materials, it will be understood that the same is also adapted to use in the distillation of liquid oils, in which event the oil is introduced to the retort and passes through zones of progressively increasing temperatures, while the vapors are discharged from said zones through independent discharge conduits permitting these vapors to be collected without being commingled.

50 In the drawings, Figure 1 represents a vertical sectional view of the apparatus; and, Figures 2 and 3 are detail views.

Referring now more particularly to the drawings wherein like reference characters indicate corresponding parts, the numeral 1 designates a distillation apparatus or retort having suitable walls composed of any desired material and mounted in any approved manner, for example upon the base 2. Supported within the retort upon an inner casing are a plurality of circular double walled hollow stationary hearths 3, which may be composed of metal, and each hearth has its upper and lower surfaces disposed at an angle so as to merge at the inner termination

thereof in a circle, so that in section it shows as a point. The hearths are secured to the inner casing or plates 3', by rivets, welding or the like, and both this inner casing and the outer wall of the hearth are formed so as to provide flues 3² on opposite sides of the retort, as shown in Figure 2, for the passage of heating gases. Positioned within the flues are a plurality of spaced baffles 4 serving to deflect the heating gases and to cause said gases to pass through openings in the inner casing or plates 3' into the hollow portions of the stationary hearths 3. The stationary hearths 3 are made of hollow formation so as to provide passages for heating gases, thereby heating not only the upper surfaces of said hearths over which the material being treated is travelling, but also transmitting heat through the lower surfaces of said hearths to material on the corresponding next lower rotary hearths. The heating gases are preferably introduced to the retort through a feed pipe 5, which is provided with branch communications 5' and 5², for introducing the heating gases to both the stationary hearths and the rotary hearths, which will be more fully hereinafter described.

Rotatably mounted within the retort is a hollow column 6, seated within bearings 7 at one end, and the structure is provided with said seals 8 at each end of the column for preventing the escape of the heating gases introduced thereto. Carried by this column are a plurality of baffles 9 adapted to deflect the heating gases so as to cause said gases always to pass into the hollow interiors of the rotary hearths, to be now described, in a circuitous path.

Mounted upon the column is a plurality of rotary hearths 10, which are of substantially the same general arrangement as the stationary hearths 3. Rotary hearths are in form the reverse of the stationary hearths, the inclination of the upper and lower surfaces merging at their outer terminations, thus providing a passage 11 for the material, between the rotary and stationary hearths, which are substantially equi-distant from one another at all points. The rotary hearths are hollow to provide passages 10' for the heating gases, such gases being also introduced to the interior of the stationary hearths 3, through openings 6' communicating with the gas flues 3². These gases are conveyed to the retort at the lower end thereof and travel upwardly through said retort in a direction counter-current to the path of the material introduced thereto, finally discharging through the flue discharge 12, thus providing in the retort heating gases which progressively decrease in temperature as they travel through the retort. The rotary hearths may be rotated in any approved manner, but in the present dis-

closure I have mounted upon the lower end of the column a gear 13, which meshes with a worm 14' for rotating the column 6, which in turn rotates all the rotary hearths rigidly connected thereto. The column at its upper end is connected with a feed pipe 14 extending loosely through a suitable packing, and it is through this feed that material is introduced from a supply pipe by a pump or the like.

The material to undergo treatment in the retort which may be pulverized coal, an amalgam of oil and coal, or oil and graphite, finely divided carbonaceous particles, shale oils and the like, is introduced through the supply pipe into the passageways 11 formed between the various stationary and rotary hearths and progressively travels downwardly through the retort while being subjected to the heat of the gases introduced through the gas feed 5. The material is first deposited upon the inner part of the surface of the uppermost rotating hearth 10, passing between said hearth and the upper inner surface of the retort wall, which retort wall is furnished with rabbles, then around the point of the upper rotary hearth, and then deposited upon the surface of the succeeding stationary hearth, travelling in this manner throughout its passage through said retort. To prevent, if desired, agglomeration of solid particles when a pulverized material is being treated, I place upon the bottom surface of each stationary hearth a plurality of hollow rabbles 17, which serve to keep the moving material in a constant state of agitation and also to transmit heat thereto while said material is passing over the surface of a movable hearth. These hollow rabbles may be, if desired, in free communication with the interior of the hearths and derive heat from the heating gases flowing therein as indicated. To prevent agglomeration of the material while travelling over the surface of a succeeding stationary hearth I also provide rabbles 17' attached to the lower surfaces of the rotary hearths, which constantly agitate the material and also transmit heat thereto. The rabbles 17 and 17' may be adjustably mounted upon the hearths, or spaced varying distances from one another so as always to cause the material passing over the hearth to be moved in the passageway 11 thereby preventing accumulations of said material between the rabbles on either hearth. These rabbles may be set at varying angles, and the position and number of rabbles are dependent upon operating conditions. The material when introduced is compelled to pass entirely through the retort, over the alternate stationary and rotary hearth surfaces, through the passageways 11 and as a result of the countercurrent travel of the heating gases the material

is subject to a progressively increasing temperature which is highest at the point where the material is being discharged.

When treating materials for recovery of their volatile constituents, it is desirable to remove the volatilized vapors at various points in the apparatus so that vapors of one character removed at one temperature may be separated and segregated from vapors removed at another temperature. With this in mind, there is disposed as communicating with the passageways 11, a plurality of independent vapor take-off pipes 12, each pipe preferably leading to a separate point of collection and storage. This permits the vapors to be discharged from the retort, as produced and prevents the various vapors volatilized at different temperatures from commingling. Any number of these discharge pipes may be employed, and they may be disposed in any manner desired.

It will be appreciated that the heated gases indirectly heat the material passing through the retort by conduction through the exposed surfaces of the movable and stationary hearths. The material is in a state of movement and agitation when passing through the retort so that in the event a material such as comminuted coal is being treated, the residue is discharged from the retort by the elongated deflector 19 attached to the lower stationary hearth, and is collected in the receiver 20 in the form, if so desired, of finely divided carbonized particles which have not agglomerated or fused together. The recovery of the residue in finely-divided form with absence of agglomeration or fusion is made possible by means of the relatively low temperature to which the material is subjected while undergoing treatment, the fineness of the material, and the uniform and gradual application of the heat thereto, such uniformity of heat control being brought about by my improved means for transmitting heat to the material as well as for agitating same during its passage through the retort.

In practicing the invention for the recovery of a maximum yield of light oils and other by-products from pulverized coal, the coal is introduced to the retort and subjected to a gas temperature of approximately 450° C. or less, which is sufficient to distil volatiles from the coal particles, and inasmuch as these coal particles are kept in a constant state of agitation the temperature is not sufficiently high to cause a material agglomeration thereof. The degree of fineness of the material controls to a certain extent the temperature necessary and the time required to remove the volatiles. When coal ranging between 100 to 200 mesh is treated, the desired result can be obtained with a gas temperature not higher than approximately 450° C., with a treatment of approximately

30 minutes. The applied heat being approximately 450° C., the temperature actually imparted to the material is approximately 350° C. By treating the coal while 5 in a very fine state of division, under agitation and at a low temperature, a maximum quantity of light oils is recovered from the coal with a minimum percentage of fixed gases. This is possible only because of the 10 low temperature treatment and the fineness of the materials for reasons previously pointed out. This low temperature also enables hearth sections to be constructed of metal of a character favorable to heat conduction as the heat is not sufficiently high 15 to attack metal hearths.

The heating gases are, as has been before stated, of a temperature approximately 450° C., so that the heat actually imparted to 20 the pulverized material is approximately 350° C., and this has been found by me to be a temperature sufficiently high to vaporize the volatiles without changing the character thereof, and to also prevent fusion of 25 the carbon residue.

While I have disclosed the preferred embodiment of the invention, it will be understood that the same is susceptible of change within the scope of the following claims 30 without departing from the spirit thereof.

Having thus described the invention, what I claim is:

1. A retort for treating comminuted materials, comprising a plurality of hollow stationary hearths and a plurality of hollow rotary hearths, said rotary hearths being so positioned alternately with respect to said stationary hearths as to form a confined passageway therebetween, means for causing 35 the material passing through the retort to alternately flow across the surfaces of the rotary and stationary hearths and means carried by the hearths for both heating and agitating the material moving across the 40 upper surfaces of hearths next below, means for supplying comminuted material to said retort to flow through said confined passageway and means for admitting a heating medium to the interiors of said hollow hearths and the agitating means associated 45 therewith.

2. A retort for distilling carbonaceous materials, comprising a cylindrical casing, having a plurality of hollow, conical, annular hearths attached thereto, projecting radially inwardly thereof at spaced distances; a revolvable column mounted substantially centrally of said casing, having hollow, annular, conical hearths attached thereto, projecting 55 radially outwardly in said casing at spaced distances into the spaces between said stationary hearths, said revolvable and stationary hearths being so spaced as to form a confined, inclined, sinuous passageway 60 therewith for feeding the material to be

treated therethrough zig-zag in vertical section; hollow, conical rabbles projecting downwardly from the inclined lower surfaces of said hollow hearths to substantially the upper inclined surfaces of the next adjacent lower hearths; means to revolve said column and attached hearths; means to indirectly heat said material consisting solely of means to admit heating gases to the interior of said hearths; means to feed material to and through said sinuous passageway; means for discharging and separately collecting vapors from the retort at progressive intervals during the travel of the material therethrough and means for discharging the treated material from the retort. 70 75 80

3. A retort for distilling carbonaceous materials, comprising a cylindrical casing, having a plurality of hollow, conical, annular hearths attached thereto, projecting radially inwardly thereof at spaced distances, a revolvable column mounted substantially centrally of said casing, having hollow, conical, annular hearths attached thereto, projecting 85 radially outwardly in said casing at spaced distances into the space between said stationary hearths, said revolvable and stationary hearths being so spaced as to form a confined, inclined, sinuous passageway therebetween for feeding the material to be 90 treated therethrough zig-zag in vertical section; means to revolve said column and attached hearths; means to indirectly heat said material consisting solely of means to admit heating gases to the interior of said hearths; means to feed material to and through said sinuous passageway; means for discharging and separately collecting vapors from the retort at progressive intervals during the travel of the material therethrough and 95 means for discharging the treated material from the retort. 100 105

4. A retort for distilling carbonaceous materials comprising a casing, a plurality of superposed alternately disposed stationary and rotatable hearths so spaced as to define a confined sinuous passageway therebetween for material being fed therethrough, said hearths being hollow and consisting of highly heat conductive material, hollow rabbles attached to the lower sides of said hearths and communicating therewith, means for rotating said rotatable hearths as a unit, means for admitting heating gases to the interior of the lowermost hearth of each 110 of the respective sets of stationary and rotatable hearths, means for causing said gases to pass successively through each hearth and the rabbles associated therewith of each set, means for sealing said sinuous passageway 115 against ingress of heating gases or air, and means at progressive intervals in said retort for withdrawing and separately collecting vapors evolved from material passing therethrough. 120 125

5. A retort for distilling carbonaceous materials comprising a cylindrical casing, a plurality of superposed, spaced annular hearths attached to the inner surface thereof, a hollow rotatable column disposed centrally within said casing and having a plurality of spaced, hollow annular hearths attached thereto and projecting radially outwardly into the spaces between 10 the stationary hearths, said stationary and rotatable hearths being so spaced as to define a confined sinuous passageway therebetween for material being fed therethrough, hollow rabbles attached to the lower sides 15 of said hearths and communicating therewith, means for rotating said column, means for admitting heating gases to the interior of the lowermost stationary hearth, means for causing said gases to pass successively 20 through each hearth and the rabbles associated therewith of the set, means for admitting heating gases to the lower end of the column, baffle means in said column opposite the respective rotatable hearths for directing 25 said gases through openings in the walls of said column into the interior of each of said hearths in succession, means for sealing said sinuous passageway against ingress of heating gases or air, and means at progressive 30 intervals in said retort for withdrawing and separately collecting vapors evolved from material passing therethrough.

6. A retort for distilling carbonaceous materials, comprising a casing, a plurality of 35 superposed alternately disposed, hollow stationary and rotatable hearths so spaced as to define a confined sinuous passageway therebetween for material being fed therethrough, means for supporting and rotating said rotatable hearths as a unit, consisting 40 of a hollow cylindrical column having openings therein communicating with the hollow interiors of said rotatable hearths, and

means for rotating said column, baffles in said column opposite the respective rotatable 45 hearths and extending through said openings into said hearths to direct gases passing through said column into the hollow interiors of said hearths in succession, means for admitting heating gases to the lower end 50 of said column, and means for withdrawing such gases from the upper end of said column after same have traversed successively said rotatable hearths.

7. A retort for distilling carbonaceous materials, comprising a casing, a plurality of superposed alternately disposed hollow stationary and rotatable hearths so spaced as to define a confined sinuous passageway therebetween for material being fed therethrough, 60 hollow rabbles depending from the lower sides of said hearths to substantially the upper surface of the next adjacent lower hearths, means for rotating said rotatable hearths as a unit, means for sealing said 65 sinuous passageway against ingress of heating gases or air, an inlet flue leading from a source of combustion gases and communicating with the lower end of said retort, a stack flue leading from the upper end of said retort, means for dividing heating gases introduced through said inlet flue and for directing one portion of same into the interior of the lowermost stationary hearth and then 70 through the remaining stationary hearths 75 and the rabbles associated therewith in series, means for directing the remaining portion of said gases into the interior of the lowermost rotatable hearth and thence successively through the remaining rotatable 80 hearths and the rabbles associated therewith in series, and means for finally leading said gases from the uppermost hearth of each series to the stack flue.

In testimony where I affix my signature.
WALTER EDWIN TRENT.
